UNITED STATES PATENT OFFICE.

LAURENCE E. TOPHAM, OF WENHAM, MASSACHUSETTS, ASSIGNOR TO UNITED SHOE MACHINERY CORPORATION, OF PATERSON, NEW JERSEY, A CORPORATION OF NEW JERSEY.

PATTERN-COPYING MACHINE.

Application filed January 18, 1922, Serial No. 530,214. Renewed June 11, 1928.

This invention relates to pattern copying machinery and is herein disclosed as embodied in a last lathe designed especially to be used in cutting last parts, as distinguished 5 from entire lasts.

The separate cutting of last parts has been proposed before, and the prior inventions directed thereto have been characterized by much ingenuity and have offered considerable promise. It is a primary object of the present invention to advance this branch of the art still further by providing a number of improvements of a distinctly practical nature which will further the production of individual interchangeable last parts on a commercial basis, while preserving fully the important advantages secured by the prior inventions.

A fundamental requirement of the general 20 problem of last part production is that the parts must be truly interchangeable, otherwise the advantages of the separately formed last part and of the separable last are not fully secured. In one aspect the problem is 25 to obtain accuracy of cut. Accuracy is of course a desideratum in any last cutting, but for various reasons is sacrificed to a considerable extent in the production of ordinary lasts. In the production of last parts, accuracy is vital to enable the parts to fit properly when put together.

Inaccuracy of cut arises under heretofore existing practice in a variety of ways. The swing frame in ordinary use is, roughly, 40 35 inches square; the model and work are suspended in it near the two lower corners; a pressure of 20 pounds on one corner will spring it 1/4 inch, and the pressures exerted on it by the model wheel at the times of its 40 reversals of movement distort it appreciably, causing corresponding inaccuracy of cut. It is also so heavy and of such great moment of inertia that the jar of reversal of movement complicates still further the inaccuracy due 45 to its bending. This sets a very low upper limit to the speed at which the machine can be run. Indeed, if a number of lasts are cut on the ordinary last lathe at speeds ranging from 10 to 50 R. P. M. they will all be recognizable 50 different. These machines are actually run at a compromise speed of 30 R. P. M. or less and even this speed sacrifices accuracy to a noticeable extent.

These difficulties of non-rigidity and jar 55 can be ameliorated by a swing frame of short

radius, and consequent small moment of inertia and increased stiffness. But such swing frames have never come into use because of their aggravation of a further difficulty introduced by the necessity of width grading. It 60 is necessary for successful width grading that the axes of the model, work, model wheel and cutter be at all times in a common plane. The plane itself may move, but they must all stay in it. This plane will move where a 65 swing frame is used, owing to the curvilinear movement of the model and work; the width grading movement of the model wheel (or cutter) in the ordinary machines is in a straight line, and consequently cannot remain 70 in this swinging plane. The long radius of the ordinary swing frame permits only a tolerable performance in spite of the flatness of its arc of swing, and a short swing frame would, by itself, be quite impractical. At- 75 tempts have been made to solve this difficulty by the slide frame, which moves in a plane, but this has been found to cause inaccuracy through sluggishness.

Accordingly in this aspect of the invention, 80 its object is to provide a swing frame of short radius with its attendant advantages which will be practical and permit really accurate width grading. Assuming the possibility of a solution of this problem as stated, it must be recognized that there is a limit to the shortening of the swing frame radius. There must be a substantial mechanical axis, in the interest of stiffness, and there must be some three inches or so of clearance between the 85 frame and the axes of the model and work to permit the rough block to rotate. The present invention has practically secured this minimum, providing, as herein illustratively exemplified, a swing frame of only 7 inches 90 radius of swing, with half of its mass located at the center, an important feature of it being a single heavy square shaft in the axis of swing, on which the model and block carriers are mounted. This frame is practically un- 95 distortable and can be successfully vibrated 100 very much more rapidly in view of its small moment of inertia than frames of former types.

The width grading problem is met by pro- 105 viding a mechanism for handling the grading instrumentality (here the model wheel) which causes it to follow the plane containing the model, work and cutter wherever it moves. In the illustrated machine, this is 110

accomplished by moving the model wheel in a direction transverse to the direction of ordinary width grading movement to keep it in this plane.

5. Another cause of inaccuracy under ordinary practice is due to the presence of a train of gears between the model and work. As the model wheel rolls over the cone of the model any existing backlash reverses so that
- 10 the parts move to the other extremity of their possible "lost motion", and a relative discontinuity of movement between the model and block results. In ordinary last cutting this is ignored because it causes no prominent discontinuity on the complete last itself, but it is intolerable in the cutting of a last part because it would cause a noticeable and adventitious discontinuity between the contours of the joint surfaces of two separately formed
- 15 last parts. The present invention meets this difficulty by providing a novel organization comprising, as shown herein, a single unitary drive spindle arranged to drive directly both the model and work. This has brought
- 20 with it an ancillary feature of reorganization of the length grading mechanism due to the fact that the spindle must engage broad and roomy parts of the model and work, where a reliable driving grip can be secured,
- 25 such parts being conveniently the joint surfaces, whence the cutter and model wheel must move in opposite directions.

Another phase of the matter of accuracy, having a particular bearing on the question of interchangeability of individual last parts is the imperative necessity of accurately shaping and placing the joint surfaces of the last parts in respect to the foot form contour. According to the present invention, this is accomplished in the illustrated machine by providing the said single unitary drive spindle with dogs constructed to fit and cooperate with prepared surfaces on the model and block having a definite relation to the external contour of the last or to some other determining feature thereof. As herein disclosed, the prepared surface is the joint surface itself. Thus there is an unvarying relation between the fundamental gage points of the machine and the foot form, so that the relation between the foot form and the joint surface is likewise invariable.

Another feature of the invention consists in a novel construction of the length and width grading mechanism so that they can be conveniently controlled continuously by the operator in order to grade the lasts throughout irregularly according to any predetermined plan. Advantageously the setting handles are arranged conveniently to the operator's two hands and pointers are provided for the setting apparatus which move relatively over a chart so that the operator can continuously control the grading at all times.

Another feature of the invention relates to the construction of the width grading mechanism itself. It is customary, in width grading, to increase the girths of the lasts a uniform amount for each size. This causes the 70 actual grading factor to vary, throughout the series, and the movement of the setting element is even more irregular, not being even proportional to the grading factor owing to the peculiar nature of the mechanism. 75 In order to secure an equicrescent setting scale in the machines known prior to the present invention, the mechanism was changed in such a way as to destroy the pantographic nature of the reproduction, only 80 the girth measurements being preserved. The present invention deals with this difficulty by providing a width grading mechanism having an equicrescent setting scale but without any consequent impairment of the 85 pantographic nature of the reproduction accomplished thereby.

These and other features of the invention including certain details of construction and combinations of parts will be described as 90 embodied in an illustrative machine and pointed out in the appended claims.

 Fig. 19 is a diagram of the width grading mechanism.
 The frame 10 of the machine carries two 120 longitudinal V-shaped guides 12—14 along its front and a flat guide 16 along its rear. The model wheel carriage 18 slides on the guides 12, 16, and the cutter carriage 20 slides on the guides 14, 16. An intermediate carriage 125 22 slides on the guides 12, 16 for purposes which will be explained later. The carriages 20 and 22 are driven in opposite directions by a right and left hand screw 24 mounted in a bracket 26 on the main frame and driven by 130

- a spiral gear 28. This gear is driven by a spiral gear not shown, but mounted on the shaft 30, parallel to and behind the worm wheel 32, which is driven by the worm shaft 34 in the well-known manner. The shaft 34 is driven from the pulley 36 on the shaft 38 which extends clear through the machine and is driven by the pulley 40 from the stub shaft 42, by a motor not shown.
- 10 Mounted in bearings 46 on the ends of the machine (which bearings also carry the shaft 38) is the swing frame 48. This frame is designed for minimum moment of inertia and maximum resistance to twisting stress. It is 15 preferably constructed as a square bar mounted on trunnions 49 in the bearings 46. See Figs. 5 and 14. This bar carries at about its middle portion a frame 50 adjustable along the square bar, though ordinarily left permanently in a determined position. This frame carries a gear box 52 and a pedestal 54, in which is mounted a shaft 56. This shaft has on its opposite ends specialized face plates 58, 60. These are advantageously made in 25 the form of an ordinary face plate 62 with crossed keys 64 projecting from it. On these keys is mounted a special dog 66, by screws 67, fitting the keys on one side and on the other shaped to the exact angle and form of the 30 joint surface of the last part 68 to be turned (and of the model 70).
- The machine shown is arranged to cut last parts for lasts of the type disclosed in United States Letters Patent No. 1,660,478, granted 35 Feb. 28, 1928, on application of G. P. S. Cross. The parts of such a last are both faced with metal plates, and a plate 69 may be advantageously placed in the machine between the dog 66 and the model 70 or last part 40 68, of thickness equal to that of a last part plate, so that the face of the dog corresponds exactly to the face on the complementary last part. This structure simplifies the adjustment of the gage points of the machine. The 45 dog 66 is equipped with studs 71 which fit corresponding holes prepared in a preferably plane surface on the model or block, so that exact correspondence between last parts can be secured. The plane surface is preferably 50 that of the joint between the parts.
- Slidably mounted on the square bar near the ends are two dog carrying frames 72, 74. These frames are adjusted along the square bar by screws 76, 78, threaded into them 55 and mounted in any desired way on the swing frame to permit rotation but not longitudinal movements. The dogs 80, 82 are thus brought up to and embedded in the model and work. The model and work are held in the 60 machine solely by the pressure between the dogs. The adjusting screws are clamped by wing nuts 79.
- The drive (see Fig. 4) is effected from the shaft 38 as follows:—The shaft has on its left 65 end a pinion 84 which drives a train 86, 88 mounted in the left bearing plate 46. This train drives a gear 90 mounted to turn on the axis of the swing frame 48. This drives a gear 92 mounted on the swing frame, which through its shaft 94 drives the splined gear 96 mounted in the frame 72 which in turn drives the model dog 80 through a gear 98. The dog 80 is round and its drive is theoretically unnecessary, but saves wear on the model. As shown it cannot drive the model. 70 The shaft 94 extends from the gear 92 through the frame 72 into the gear box 52 where gears 100, 102, like the gears 96, 98 respectively are mounted to drive the spindle 56, through which the model 70 and work 80 piece 68 are driven.
- A vitally important feature of the present invention consists in this spindle and its attached dogs. It has long been the aim of shoe manufacturers to avoid a considerable part of 85 the expense of the provision and upkeep of lasts by using a single heel part with a plurality of foreparts. This necessitates that the parts be absolutely interchangeable, and this requirement has impeded the achievement of commercially practical results by any of the solutions of the problem proposed by previous inventors. It has been proposed to sever the rough block into a heel part and forepart, join them by a bonding mechanism 90 and then turn the last. This procedure, while competent to make one good separable last, does not insure that the joint surface will be placed uniformly in different lasts, since any 95 variations in the rough block's terminal contour and dog penetration for example affect the longitudinal position of the last in the rough block, and the parts thus formed may not be interchangeable.
- It has also been proposed to sever the block 100 as above stated and turn the last parts independently, the foot contour being shaped in some definite geometrical relation to a (preferably plane) surface having a useful function in the last; such surface being generally 105 the joint surface between the heel part and forepart. While the prior inventions along this line offer great promise, I believe that further improvement is still possible, especially 110 in the elimination of one mechanical difficulty 115 which has strongly militated against their success. In the last lathe as ordinarily constructed, the model and work are driven, one from the other, through a train of gearing in the swing (or slide) frame. A certain amount of backlash is always present in such apparatus, and gives rise to such difficulties 120 as the following:
- When the model wheel is rolling up over the model cone, the reaction between the two crowds the model backward against its driving gears; after the wheel passes the cone and begins to roll down, the reaction crowds the model ahead against its driving gears. An 125 inaccuracy in reproduction results from this 130

shifting of the backlash from one extreme to the other. This inaccuracy is variable and more or less casual, and where a last part is being formed which is to fit other last parts 5 formed in other operations, and on other machines, it prevents the accuracy of registration necessary in their surface contours about the joint. This difficulty is entirely eliminated by the construction described. The model 10 last part and the block are rigidly integrally held in relation to the same spindle, and whatever happens to one must happen to the other, as far as this difficulty is concerned, since there is no backlash between them.

15 The swing frame shown has other important advantages, aside from its peculiar relation to the matter of last-part production. A difficulty which has always given trouble in last cutting, and which is avoided by the construction shown, may be illustrated as follows: Suppose the model to be a truncated circular cone, swung on its axis in the swing frame, and that the cutter and model wheel are traversed over the work and model without 20 rotating the model and work. The point of contact of the model wheel on the model will not stay in the same plane passing through the axis of the cone since as the swing frame turns more or less to accommodate 25 the varying diameter of the model, the point of contact will move around the model. Another way of stating the difficulty is to suppose that the model swells while the machine is motionless. The point of contact, as it 30 moves outward from the model axis, will not stay on the same model radius. This matter, in case normal 1:1 reproduction is being done, does no harm, because the model and work have the same treatment, but if the 35 model and work are rotated in opposite directions in order to take care of the right-and-left question, it introduces inaccuracy. This difficulty has been dealt with in the past in two ways:

40 1. By providing a slide frame, which does not rotate at all; 2. By providing a swing frame of long radius of swing, so that a swing of 3 or 4 inches has small angular magnitude. These solutions are accompanied by 45 characteristic disadvantages. The slide frame is sluggish and has too much unavoidable friction inherent in its construction. The long swing frame has a very large moment of inertia and is too flexible unless made 50 so heavy as to cause really destructive jar. Such flexibility and jar cause unequal "depth of cut" on model and block.

55 This problem and the attendant disadvantages of the heretofore known solutions are 60 dealt with by the present invention as follows: It is only 7 inches from the spindle 56 to the axis of the bar 48, and the square bar insures great relative rigidity of parts mounted on it. The gear casings are made 65 of aluminum, and the mass is concentrated

very largely around the axis 48. In the machine shown, 50% of the mass of the entire swing frame, model and block is in the bar 48. The moment of inertia is very small about this axis, and the jar of reversal of movement consequently minimized. It has proved possible to run this machine at 50 or 60 R. P. M. with less jar than is experienced on the Gilman machine at 30 R. P. M. This enables me to secure the same rate of production as on the Gilman machine, and at the same time to shorten the feed so that the product does not have to be smoothed, so that an item of highly skilled labor is avoided.

This shortening of the radius of the swing frame of course tends to accentuate the above-described difficulty due to rotation in following work of varying diameter. This difficulty is, however, entirely removed by a feature of the construction disclosed. The gear 96 has exactly half as many teeth as the gear 98, the gears 90 and 92 are equal and the distance on centers between the shafts 48 and 56 is designed equal to the distance from the center of the shaft 48 to the center 103 of the model wheel 104 in its normal or "zero" position. This position is in alinement with the cutter center. If now the gears 88-90 are fixed and the swing frame rotated, a radial line 106' (Fig. 11) of the gear 98 which passes through the center 103 of the model wheel will always pass through it, irrespective of the position of the swing frame. This appears from Fig. 11. Suppose the parts originally in the full-line position, with the angle Ψ' between the swing frame and line 48-103, and with the model radius 106' passing through the center 103. Since the triangle 48-103-80 is isosceles, the angle at 80 is $90^\circ - \frac{1}{2}\Psi'$. Let the frame swing out counterclockwise through an angle Φ' . The gears 92 and 96 will be rotated thereby counterclockwise an angle ϕ' with regard to the swing frame. The gear 98 will therefore turn a clockwise angle of $\frac{1}{2}\phi'$ with regard to the swing frame and the angle at 80' made by the same radius 106' of the gear 98 will be $90^\circ - \frac{1}{2}\Psi' - \frac{1}{2}\phi'$ which is the base angle of an isosceles triangle 80'-48-103. The same radius 106' will therefore continuously point 105 to the center 103 of the model wheel 104 irrespective of the position of the swing frame.

The novel subject-matter set forth in the preceding paragraph is not claimed herein, but is claimed in my continuing application, 115 Serial No. 284,078, filed June 9, 1928.

It will be noticed that a cross-section of the shaft 48 has one diagonal in the plane containing its axis and the axis of the spindle 56. This structure has a peculiar advantage. If there is any looseness in fit of the frames 72, 74, when they are tightened up against the model and work, they will rotate slightly and cramp on the shaft and the dogs 80 and 82 will always settle into this plane be- 120 125 130

cause of the double V action, no matter how loose the frames are, and their distances from the axis of the shaft 48 under normal conditions will not be substantially affected.

- 5 The model wheel 104 (see Fig. 4) is carried on a slide 106 having forward and back horizontal movement transverse to the direction of feed of the model wheel carriage, and normally held back by the spring 107. The 10 forward horizontal movement is effected by a rod 108 pivoted to the slide at 110, and contacting through a roller 112 with a fan board 114 pivoted on an axis at 116 and operated by a link 118 joining it to the swing frame as is 15 well understood. Fig. 4 (see also Figs. 2 and 19) shows a mechanism for irregular width grading around the periphery of the work. This mechanism is described and claimed in my application, Serial No. 429,719, 20 filed December 10, 1920, and will be only briefly described here. The fan board is 25 cylindrical in form, the center of the cylinder being at the center 110 when the swing frame is in an adopted "zero" position, shown in dotted lines in Fig. 19 as 114' so that adjustment of the width grading factor can be made without moving the grading slide 106. A long pinion 120 on the shaft 38 operates a gear 122 which slides along it, being mounted 30 on the model wheel carriage, and which carries a cam 124. The gearing is such that the cam 124 and the model and block rotate with equal angular velocity. The cam operates a roller 126 on a crank arm 128, spring held at 35 129, of the segment 130 which is pivotally mounted at 132 on the model wheel carriage. The slot shown in this segment carries a block 134 pivotally carrying the end of a link 136, which is joined to the rod 108. The lower end 40 of the link 136 is shown directly over the pivot 132 in Fig. 4, but can be adjusted anywhere in the segmental slot by a link 138 pivoted to a rigid arm 139 on a segment 140, pivoted at 45 141 and operated by a worm 142 on the shaft 144, by a handle 146 at the front of the model wheel carriage. A dial 147, geared to the shaft, indicates the setting. The radius of the slot in the segment 130 is equal to the length of the link 136. A certain "zero" position 50 of the segment 130 corresponds to ordinary width grading, which will result from its being placed in this position and the block 134 being adjusted to the point desired. With the parts as shown in Fig. 4, with the 55 roller 112 at the fan-board center 116, if the segment 130 is swung to the position where its center of curvature falls on the pivot at the upper end of the link 136, the width grade will be zero, irrespective of the adjustment 60 of the block 134. For the purposes of the present application it is enough to say that the cam 124, by rotating the segment 130 with proper adjustment of the block 134 causes a continual variation in the setting of the link 108, so that the width grading function is

cyclically varied, the cyclic period being that of the rotation of the model and work. This enables me to grade lasts of two different widths with the same insole pattern, for example.

Another important feature of the invention will now be described (see Figs. 4, 10 and 19). If width grading is to be done, it is necessary for the model wheel to be given a special movement in order to keep it in the plane containing the spindle 56 and the cutter center, since the horizontal width grading movement of the slide 106, if uncorrected, will carry it out of this plane. Remembering that an angle inscribed in a circle is measured by half the intercepted arc, it will be seen from Fig. 11 that it is necessary, in effect, to rotate the grading slide 106 about the zero position of the model wheel center, which is in line with the cutter center, just half as rapidly as the swing frame rotates. The mechanism for accomplishing this result is as follows:—

Pivoted at 148 on the grading slide 106 is a lever 150 formed as a double crank, one crank on each side of the slide 106. The forward arm carries the model wheel 104, and the rear arm carries a laterally extending slide 152 rotatable about a horizontal axis 153 (Fig. 10) on the lever 150. Mounted on a horizontal stub shaft 154 rotatable in the main body of the model wheel carriage 18 is a slideway 156, carrying the slide 152, on one side of the slide 106, and an arm 158 on the other side. The arm 158 is linked to the fan board by a link 160, which slides along a rod 162 at the top of the fan board as the model wheel carriage moves along the bed. It is steadied by a strap 164 on the outside. As the fan board tilts in obedience to the swing of the swing frame, it turns the shaft 154 and slideway 156. As seen in Fig. 4, when the swing frame moves counter-clockwise, the fan board moves clockwise, as does the slide 156. If the width grader is set to grade up, the grading slide 106 will move out as the swing frame does. As this occurs, the parts 152—156 will tilt the lever 150 clockwise and cause the model wheel to rise as it moves out, but as the swing frame moves farther and farther, the slide 156 becomes horizontal and then tilts in the opposite direction to that shown in Fig. 4, so that the model wheel, after rising for a time, begins to fall, thus always moving toward the center 80. The slideway 156 is in effect a cam which can be shaped to produce exactly the desired movement of the model wheel.

The shape of this cam may be determined as follows. See Fig. 12 in which o represents the center of the shaft 48 and a represents the center of the cutter 165 and the zero position of the center 103 of the model wheel 104. The model wheel and cutter are here shown as of circular projection, of radius approximately equal to the effective radius of the elliptical projection of the model wheel and cutter used.

Fig. 12 is drawn approximately to scale. The axis of the model and work 56 is represented at c ; d represents the fulcrum 148, and b the pivot 153 at the rear end of the lever 150, which is therefore adb . The radius of the model being treated is cm' , and it is necessary that the point a move down to a' along the line ca , by swinging the line adb around the point d , which slides along the line hab by virtue of the ordinary width grading movement. This brings the line into the position $a'd'b'$, and the rotating slide way 156 must be such as to move the point b to b' . The point k is the position of the center c where no correction is needed to the grading slide movement, that is, where the slideway 156 is horizontal; and the angle Ψ is a constant of the machine. Put:

- 20 g = the grading factor.
 R = the radius of the model wheel.
 $cm' = r$ the radius of the model.
 $ad = a'd' = n$.
 $db = d'b' = p$.
 $oc = oa = q$.
25       $eb' = y$.
 $be = x$.

In the triangle $a'ad'$

$$30 \quad \begin{aligned} a'd' &= n \\ a'a &= m'm = (g-1)n \\ \text{angle } a'ad' &= 180^\circ - \frac{1}{2}\Theta \end{aligned}$$

$$\therefore \sin ad'a' = \sin \phi = \frac{(g-1)r}{n} \sin \frac{1}{2}\Theta \quad (1)$$

$$35 \quad y = d'b' \sin \phi = \frac{p(g-1)r}{n} \sin \frac{1}{2}\Theta \quad (2)$$

The projection of aa' on ab is $aa' \cos \frac{1}{2}\Theta = (g-1)r \cos \frac{1}{2}\Theta$ and therefore

$$40 \quad x = (p+n)(1-\cos \phi) + (g-1)r \cos \frac{1}{2}\Theta \quad (3)$$

We have also

$$45 \quad \begin{aligned} \sin \frac{1}{2}(\theta + \Psi) &= \frac{ca}{2q} = \frac{gr+R}{2q} \quad (4) \\ \sin \frac{1}{2}\Psi &= \frac{ka}{2q} \quad (5) \end{aligned}$$

In the machine disclosed, as actually constructed,

$$50 \quad \begin{aligned} R &= 1.58 \text{ inches.} \\ n &= 3 \text{ inches.} \\ p &= 6 \text{ inches.} \\ q &= 7 \text{ inches.} \\ ka &= 4.75 \text{ inches.} \\ \text{whence by (5)} & \Psi = 39^\circ 40' \end{aligned}$$

When the center c is at k , that is when $\Theta = 0$, no correction to the movement of the grading slide is needed. Then by (4) and (5)

$$60 \quad \begin{aligned} \frac{ka}{2q} &= \sin \frac{1}{2}\Psi = \frac{gr+R}{2q} \text{ whence (6)} \\ gr &= 3.17 \end{aligned}$$

Now a width grade of 7 sizes from a men's 65 #7-C gives a grading factor of about 1.2.

For the special condition above noted, if $g=1.2$, $r=2.6$, which is a greater radius than is found anywhere on a men's #7-C. This means that most last turning even when grading will be done with the center c between k and a ; that is, that Θ is generally negative in last turning and when positive, is small. Fig. 12 has however been drawn as if the model were much larger, in order to avoid crowding of the lines in the $a'ad$ neighborhood.

Now obviously, if we could drop out the $(p+n)(1-\cos \phi)$ term in (3) we would have simply, from (2) and (3)

$$80 \quad \frac{y}{x} = \tan b'be = \frac{p}{n} \tan \frac{1}{2}\Theta \quad (7)$$

and if we make the special assumption that $\frac{p}{n} = 2$, as in the described machine, we have 85

$$\tan b'be = 2 \tan \frac{1}{2}\Theta = \tan \Theta (1 - \tan 2\frac{1}{2}\Theta) \quad (8)$$

which is independent of the grading factor g and of the model radius r , depending only on Θ . Now if we could also suppress the factor $(1 - \tan 2\frac{1}{2}\Theta)$ we would have simply

$$90 \quad \tan b'be = \tan \Theta \quad (9)$$

for any position of b' . In other words, the slideway 156 could be straight, and its rotation from the horizontal position (which corresponds to the position of c at k) would equal the angle Θ . In still other words, if the swing frame be swung to a certain position Θ and held there, and the model be swelled or shrunk and be followed by the model wheel, by suitable continuous variation of the width grader setting, along the line $ca'a$, the pivot b (153) would travel on a straight line bb' , whose position depends only on the value of Θ .

Taking the last matter first, the maximum numerical value of Θ is 108° in Fig. 12, so that the model axis lies on the face of the model wheel. Putting $r=o$ in (4) we find o to be $-26^\circ 42'$. This condition is approximated in cutting the upper surface just behind the toe of some types of lasts. Now

$$110 \quad 1 - \tan^2 (-13^\circ 21') = .944$$

and therefore a maximum error of about 5% in the slope of the slideway 156 is involved in this approximation. Further, this maximum value of Θ corresponds to the condition where the grading movement of the model wheel is very small so that a correspondingly small actual error in the cutting actually results.

In the matter of $(1 - \cos \phi)$ we proceed as 125 follows: For any given value of Θ , gr becomes a constant, by (4) and the value of $\sin \phi$ depends only on $(g-1)r$, by (1). This will be a numerical maximum when r is a minimum, since gr is constant; and r is a 130

minimum when g is a maximum, for the same reason. We have suggested $g=1.2$ as the

maximum grade in last cutting, and we then have,

$$(g-1)r = gr - \frac{gr}{g} = gr \left(1 - \frac{1}{g}\right) = gr \left(1 - \frac{1}{1.2}\right) = \frac{gr}{6} \quad (10)$$

5 whence, from (1) after solving (4) for gr :

$$\sin \phi = \frac{14 \sin \frac{1}{2}(\Theta + \Psi) - 1.58}{18} = \sin \frac{1}{2}\Theta \quad (11)$$

which has its maximum value at $\Theta = -13^\circ 24'$

10 whence, from (1):

$$\begin{aligned} \phi &= -0^\circ 36' \text{ and} \\ 1 - \cos \phi &= 0.000055 \quad (12) \end{aligned}$$

so that the $(1 - \cos \Phi)$ term in (3) amounts to 15 only .0005 inch at most; the maximum horizontal error in the position of the model wheel center is half that amount, and is utterly negligible; and α is therefore given within the limits of accuracy in woodworking by

$$20 \quad x = (g-1)r \cos \frac{1}{2}\Theta \quad (13)$$

The error in y due to our approximation may be found as follows: From (2) the true y is

$$25 \quad y = 2(g-1)r \sin \frac{1}{2}\Theta \quad (14)$$

and the approximate y given by the machine is

$$y = \alpha \tan \Theta = (g-1)r \cos \frac{1}{2}\Theta \tan \Theta \quad (15)$$

30 The error in y is the difference between (15) and (14) or

$$dy = (g-1)r(\cos \frac{1}{2}\Theta \tan \Theta - 2 \sin \frac{1}{2}\Theta) \quad (16)$$

35 For any definite value of Θ , we have as before, the greatest value of dy at $g=1.2$. We then derive, in the same way as in the case of (11)

$$40 \quad dy = \left[\frac{7}{3} \sin \frac{1}{2}(\Theta + 39^\circ 40') - 0.263 \right] X \left[\cos \frac{1}{2}\Theta \tan \Theta - 2 \sin \frac{1}{2}\Theta \right] \quad (17)$$

45 The maximum value of this expression occurs at $\Theta = -20^\circ 14'$ and is -0.0015 inch. The vertical error in the position of the model wheel center is one half as great.

Thus the errors in the placing of the model wheel, when g runs from 0 to 1.2 are less than 0.0003 inch horizontally and 0.0008 inch vertically, assuming the slideway 156 to rotate exactly with the swing frame. Exact relationship of this kind is of course procurable by a rack and pinion connection, but the link motion shown produces quite satisfactory results, as would be obvious from the fact that the angle Φ does not exceed $0^\circ 36'$ in last cutting.

55 The investigation for a diminishing grade need not be given here. The analysis is quite similar, and the exact performance of the machine under all circumstances can be deduced from equations (1)–(5).

The artifice of placing the center 103 be-

hind the center 48 substantially diminishes the errors of the machine. If these centers 65 were in the same vertical line the error would increase continually as c moved from s . With the machine as it is, the error increases as c moves from s and then diminishes again as c approaches k .

70 A directly motor driven cutter is shown at 165. In view of the fact that the axis of the model wheel and cutter are inclined at about 30° with and toward the direction of feeding travel (this feature is explained in 75 United States Letters Patent Nos. 1,137,117 and 1,330,841, granted on the applications of F. S. Buck), it is necessary to provide that the tipping of the lever 150 shall not carry the axis of the model wheel out of horizontal. 80 This is accomplished by pivoting a link 166 in line with the center 103, on the effective end of the lever 150. This link is joined to the slide 106 by a second link 167, equal in length to the distance 103–148, and 85 with its inner end located vertically below the point 148 at a distance equal to the effective length of the link 166. The link 166 must therefore always remain vertical. The model wheel spindle projects from the side of the 90 link 166 at an angle of 30° , as is well shown in Fig. 2, and will always remain horizontal.

95 The disclosed machine is equipped with a mechanism for stopping the spindle 56 in the same orientation to facilitate the convenient insertion and removal of work. The pulley 40 is rotatably mounted on the shaft 38, and is connected with it by a laterally sliding clutch (not shown). This clutch is operated by a lever 168 by pushing its outer end outward, which is accomplished by the following mechanism: A bell-crank lever 169 (see Fig. 3) has a notch in its upper surface which catches a pin 170 on the swing frame when the frame is pulled out by the operator. It 105 also has another notch 172 in which rides a finger 174 of the rod 176, pivoted to a bell crank 178 at the back of the machine (Fig. 3). This bell crank carries pivotally at 180 a rectangular bar 181. This bar has a bevel 182 110 which is at an angle with the surface seen in the plane of the paper and with the left-hand surface perpendicular to the plane of the paper in Fig. 3. When the swing frame is pulled out it drags on the finger 174 and pulls 115 it out to the notch 172. This pushes down the bar 181 until the bevel 182 contacts with the clutch lever 168 (but does not throw it). A little pinion (not shown) on the shaft 38 drives a gear 184 at the same angular velocity 120 as that of the spindle 56 in the swing frame. A cam 186 mounted on the gear 184 thrusts

the lower end of the bar 181 to the left in Fig. 3 when the spindle 56 has reached the desired orientation and the bevel 182 then throws the clutch lever. The carriage feed is 5 connected at 188 (Fig. 1) in the manner well known in the Gilman lathe so that no danger results if the operator is not present.

Fig. 1 shows the ordinary type of length 10 grading lever 190 linked to the carriage 22 by an adjustable link 192 and pivoted on the carriage 18.

A special fixture is shown in Fig. 1 to fit a 15 definite length grading problem. The block 194, instead of being adjusted as ordinarily, is provided with four studs 196. An arm 198 is mounted at an angle with the vertical on a block 200 on the carriage 22. The block is 20 adjustable along the carriage by a screw 202, and the arm 198 carries four corresponding 25 studs 204. The mounting of the link 192 on any pair of corresponding studs adjusts the machine for a predetermined length grading problem.

A preferred arrangement of the grading 25 mechanisms is shown in Fig. 8. The model wheel carriage 18 carries an apron 206 on which is mounted a shaft 208 geared to the shaft 144 at 210, and to the lever 212 at 214. The lever is pivoted at 213. Movement of 30 the handle 146 therefore will operate a pointer 216 on the lever 212. The apron also carries a three-armed lever 218 pivoted at 219 having a pointer 220 on one arm, a gear connection 222 with a shaft 224 on another 35 arm, and having a link 226 connecting the third arm 228 with the block 200. The length grading mechanism here is not automatic at all, the distance between the carriages 18 and 22 being fixed except when being varied by 40 means of the handle 228, on the shaft 224. Curves 230, 232 drawn on a chart 234 fixed on the front of the machine frame 10 serve the operator as guides for continuous control of the graders while the cutting is being done.

45 This chart may be advantageously formed as follows (Fig. 13); a board or table 236 having a graduated rail 238 graduated in inches along one edge is provided with two template holes 240, corresponding to the holes 242 in the front of the machine. The chart paper is pinned by these holes in each case. A slider 244 is provided to move back and forth along the guide rail. The edge 246 of the slider is a nearly circular arc having the 50 same orientation and vertical relation to the holes 240 as that of the path of the pointer 220 to the holes 242, when the pointer is moved with the carriage 22 at rest. (The carriage 18, on which the pointer is pivoted, moves slightly with the adjustment, so that the path of the pointer in space is not a perfect circle.) The edge 246 of this slider is 55 graduated, the units representing for example, a 1/24 inch alteration in the distance between the carriages 18 and 22. The zero point 60

248 represents the position of the pointer when the carriages are so adjusted that the centers of the model wheel and cutter will simultaneously align with the axial centers 250 of the faces of the dogs 66 (Fig. 6). If 70 now a horizontal line 252 be drawn on the chart opposite this zero mark and the pointer 220 set on it and left there, the model will be exactly copied as far as longitudinal dimensions are concerned. Suppose that the model 75 measures 13 inches over all, divided into two sections of 10 inches and 3 inches from the ends to the axial point in the joint surface (corresponding to the point 250 in Fig. 6, neglecting the position of the joint plate). 80 Suppose that the thickness of the model wheel and cutter is 1 inch. Then the model wheel has to travel 10 1/2 and 3 1/2 inches, respectively, in cutting the forepart and heel part. The end 254 of the slider is set at 10 1/2 85 on the scale 288, and a line 255 drawn down along the edge 246 on the chart paper. The slider is then moved until the point 254 comes opposite the -3 1/2 graduation of the scale 238 and a mark 256 made at the intersection 90 of the edge 246 and the line 255. Suppose now that we want to make a last which is effectively 1/3 inch longer than the model. Draw a line 258 from the point 256 to the +1/3 inch point on the line 255. If now the 95 paper be mounted in the machine and the pointer 220 kept on the line 258 by the operator's use of the handle 228, the ordinary length grading operation will be accomplished. The elongation of the heel part 100 corresponding to this operation is represented by the distance 249.

Suppose now for example that we want to 105 cut a last belonging to a set in which all the foreparts of a group fit the same "standard" heel part; in which a group of lasts will have the same insole pattern, and a group of lasts will have the same toe tip, for example, for the general purpose of standardizing shoe manufacture and reducing its expense. Suppose 110 also that our last in order to fit the group insole is actually to be 9/24 inch longer than the model, while having the longitudinal foot room of a last 8/24 inch longer. Suppose also that it is to have a "standard" toe tip 115 which is just like the model tip. Draw a line 260 on the chart parallel to the line 252 and passing through the +9/24 point of the line 255, and make it as long as the "standard" toe tip. Draw a line 262 dropping rapidly 120 and easily to the line 258. Suppose now that the standard heel part to be used with the set to which this forepart belongs is, instead of 3 inches + the elongation 249, to be actually 3 inches + the elongation 264 and that it 125 is to be formed by regular grading from the model heel part. The line 266 corresponds to the regular grading of this heel part from the model heel part. This line 266 is extended far enough beyond the zero of the scale 238 130

to cover the point 268 (Fig. 6) and a line 270 is drawn to blend the line 258 into the line 266. If now the pointer 220 be made to follow the curve 260—262—258—270—266, 5 the forepart will fit the standard tip and insole, and will be graded in the instep, where fit is important, strictly according to the ordinary system, and will fit the heel part common to the set at its rear end. The line 260 10 copies the model toe tip exactly, the line 258 stretches the ball-instep portion in the proper fashion, and positions it in proper relation to the heel end 256; the line 270 shortens the model just behind the instep, to allow for the 15 oversize heel part; and the line 272 grades the part just in front of the joint so that it will just fit the heel part.

The width grading problem may be similarly solved. The tip length should be 20 graded directly from the model. Suppose the ball and instep portion is to be graded up $1/4$ inch (in perimeter) and that the "standard" heel part is constructed as for a 25 last whose ball-instep portion is being graded up $5/16$ inch. The other edge 274 of the slider 244 is formed on the curve traced by the pointer 216 when the carriage 22 is motionless, and the edge is graduated. The width grader is automatic, and all that the handle 30 146 does is to change the grading factor so that the scale 274, if graduated in units of girth change, as is convenient, will vary with the model used. We will suppose that we have a scale 274 graduated in $1/16$ inch 35 changes in perimeter for the model being used.

Suppose the worm at 214 to be such as to throw the pointer 216 up when grading up, and that the parts are designed so that the same line 252 is the zero width grade line. With the end of the slider at $10\frac{1}{2}$ on the scale 238, mark the point 276 at the intersection of the line 252 and edge 274. Move the slider along the length of the toe tip to 277 45 and mark a point 278 at the $4/16$ point of the scale 274, and draw a line 280 from the point 278 parallel to the line 252. Draw the line 282 from the line 252 at 277 to blend into the line 280. Then move the slider until its end 50 254 is at the zero of the scale 238, putting the edge 274 at 284. Draw a line 286 through the $5/16$ point of the scale 274, and blend the line 280 into the line 286 by a line 288 just before the point corresponding to the point 268 is 55 reached.

By the use of such a chart in connection with the equipment shown in Fig. 8, the operator is enabled to cut lasts having such peculiar and miscellaneous characteristics as 60 those described, and the operation is rendered so simple as to require little skill on his part.

Another important feature of the present invention consists in an accurate pantographic width grading mechanism with an 65 equicrescent setting scale.

Width grading mechanisms as found in the machines heretofore in use are subject to a serious fault, arising as follows: In width grading the successive members of a set of lasts increase in girth by constant amounts. 70 If the radius of the model is r , and the magnification factor is g , the swing frame must be moved a distance gr from the face of the cutter and the model wheel must be advanced $(g-1)r$ from its "zero" position to hold it 75 there. The fan board moves proportionally to the swing frame, so that the width grader feeler setting is proportional to

$$\frac{(g-1)r}{gr} = \frac{g-1}{g}$$

80

We can assume the factor of proportionality to be unity without loss of generality. In the following table are shown the ball girth measurements of a set of 13 lasts, the factors 85 g necessary to produce them from a 7C model, and the width grader settings,

Size	Girths	g	$\frac{g-1}{g}$	90
7 AAAAA	28/4	28/34	-6/28	
AAA	29/4	29/34	-5/29	
AA	30/4	30/34	-4/30	95
A	31/4	31/34	-3/31	
B	32/4	32/34	-2/32	
	33/4	33/34	-1/33	
7 C	34/4	34/34	0	
D	35/4	35/34	+1/35	
E	36/4	36/34	+2/36	
E	37/4	37/34	+3/37	
EEE	38/4	38/34	+4/38	100
EEEE	39/4	39/34	+5/39	
EEEEE	40/4	40/34	+6/40	

It is obvious that the scale of grader settings is not equicrescent, the intervals at the lower end being larger than those at the upper. An equicrescent scale was regarded as a necessity for the class of operator who runs these machines, and the difficulty was dealt with as follows. Suppose an equicrescent scale averaging the desired settings over the 105 range indicated to be put on the machine. This would increase the grader setting $1/34$ per size. The 7 AAAAA setting would then be $-6/34$ and the 7 EEEEE setting would be $+6/34$. Now $6/34$ is numerically smaller than $6/28$, by more than $1/6$ of the whole setting, indeed, the setting for the 7 AAAAA is just about what it ought to be for that 7 AAAAA, so that on the 7 AAAAA the model is not "shrunk" enough. Also $6/34$ is larger than $6/40$ (which is about $5/34$) so that on the 7 EEEEE the model is swelled too much. At the extremes the settings would be about a size out, each way. To correct this, the fan board 114' was backed off each side of its axis 116' (see Fig. 18) so as to present a flat wedge to its feeler 112'. As the feeler was moved either way from the zero position, it would let the model wheel settle back from the swing frame by an amount constant for 110

115 the swing frame by an amount constant for 120 the swing frame by an amount constant for 125 the swing frame by an amount constant for 130

that setting, which resulted in grading in effect from a model that was that much (arithmetically) too thin all over. This would decrease the girths of all lasts cut except the model width, and would tend to correct, in one aspect, the error introduced by the equicrescent setting scale.

It is obvious, however, that the results were not pantographic reproductions of the model at all, but of a model equivalent to the model minus a layer of uniform thickness all over. All width grading on machines heretofore in use is affected by this error.

The present invention provides a machine having a substantially pantographic width grading mechanism of the range indicated in the table above given, with a substantially equicrescent setting scale. This is accomplished as follows; see Fig. 19.

Assuming a grade of 6 sizes up on a model 9 inches in circumference, the work will be 10½ inches in circumference. These are shown at 70 and 68 in Fig. 19. The work must be tangent to the cutter 165, and the center of the model wheel 104 must be advanced to 103 (along a straight line from the cutter center 306 to the spindle center 56) to hold the swing frame 72 in the proper position. This enables us to lay out the position of the fan board 114, and of the slide 106. The former is done by finding the position of the left end of the link 118 in accordance with the position of the swing frame 72, whence spanning across to the circle 300 in which the end of the fan board swings, we get the fan board position. The center of curvature of the fan board swings up to 302. The position of the slide 106 is found from the model wheel position 103. The point 110 must move to the left from its zero position 304 (which corresponds to a position of the spindle 56 in line with the cutter face), an amount equal to the horizontal projection of the short line 306—103, 306 being the zero position of the model wheel center, and the position of the cutter center. The link 108 may then be spanned from 110 to the fan board, giving the position of the roller 112. As a practical matter, since the length of the link 108 equals the radius of curvature of the fan board, the point 112 is the apex of an isosceles triangle with base 110—302. This intersection is a little easier to plot.

The segment 130 is drawn in its zero position, corresponding to ordinary width grading, and the link 136 may be spanned across to find the point 308. In like manner the points 309—316 can be located on the segment 130, corresponding to each size and a half of ordinary width grade up and down from the model, as far as 6 sizes up and 6 sizes down. The particular points taken arise from a special problem in connection with which the machine shown was designed.

The draftsman will then experiment until he finds a point 141, an arm 139, and a link 138, connecting the ends of the arm 139 and link 136, such that the turning of the arm 139 by the handle 146 by eight successive substantially equal angles measured on the dial 147 will move the end of the link 136 into the eight successive positions 309—316.

The possibility of an approximate solution is clear from the following:—The position of the point 141 involves two "coordinates" (up and down and right and left), which are at our disposal. The lengths 139 and 138 supply two more and the angle between the successive positions of 139 and the general orientation of the whole set of positions of 139 involve two more. There is therefore a solution which will fit any chosen six of the nine points 308—316 exactly. This is substantially what the draftsman accomplished in the solution plotted in Fig. 19. The positions of 139 for the points 308, 309, 310, 315, 316 are not out by as much as the thickness of the lines; the positions for 311 and 314 are perceptibly out, and for 312 and 313 are approximately 10% of one size out. As compared with the prior machines, which, if equipped to grade pantographically, would be a whole size out at each end of the range, with corresponding errors everywhere else, if provided with an equicrescent scale, the superiority of the present invention is apparent.

If still greater accuracy is desired, a bell crank 320 may be pivoted on the arm 139 with one of its arms pivoted to the link 138, and with its other arm engaging a cam 322 on the frame of the machine. This cam will be nearly circular about the center 141.

In the above discussion, it is to be understood that we have left out of account the question of varying the shape and size of the model wheel relatively to those of the cutter in accordance with the magnification factors being used. This is theoretically necessary, but in practice is never done, in any machine. If the model wheel and cutter are reduced to the geometrical points which they are in theory the grading mechanism described will be strictly pantographic, and the language used is quite accurate.

Another feature of the invention will now be described. It may be found advisable, under some conditions, to form the dividing cut of the last in such a way that it will have different relations to the toe tips in lasts of varying styles. This might necessitate a great many special dogs 66, in order that the tip of the last part be placed in the axis of the spindle 56. In order to permit the use of the dogs 66 with a considerable range of style in the lasts, I have provided a special toe dog holding plate 330 (Figs. 15, 16 and 17) provided with four threaded holes 332. These holes are all eccentric, and are prefer-

ably placed as shown by the heavy dots in Fig. 17. These dog holders are alike on both sides, can be put on either side out, and rotated into any of four possible positions 5 90° apart. A little consideration will show that suitable positioning will put some one of the threaded holes in any desired one of the 10 16 positions shown in Fig. 17. For example, the plate 330 as shown in Fig. 16 places the 15 holes as shown by the black dots in Fig. 17. When the plate is turned the other side out (Fig. 15) without change of orientation in its plane, the holes are placed like the circles in Fig. 17. The plate of Fig. 16, when 20 rotated 180° in its plane will place its holes like the $\times$ marks in Fig. 17 and when turned "wrong side out" in this orientation will place the holes like the $+$ marks in Fig. 17. The dogs 80, 82 are made to screw into the 25 holes and thus a considerable flexibility is secured in the use of the dogs 66.

While the invention has been disclosed in connection with a machine for turning last parts as distinguished from complete lasts, 30 it will be obvious that many of the advantages of the invention are obtainable in connection with the turning of complete lasts.

Having described my invention, what I 35 claim as new and desire to secure by Letters Patent of the United States is:—

1. In a pattern copying machine, a pivoted swing frame having an effective radius of swing exceeding the radius of the mechanical axis by not substantially more than the maximum radius of the work-block to be handled, 40 a model wheel, and width grading mechanism for moving said wheel from the position in which it effects 1:1 reproduction and for keeping its center upon a line joining this position and the axis of a model carried in the swing frame.

2. In a pattern copying machine, a pivoted swing frame having an effective radius of swing approximating the minimum permitted by the requirement of clearance between the mechanical axis and the work-block, a model wheel, and width grading mechanism arranged to move the model wheel so that a plane can be passed through (1) the axis of a model in the swing frame, (2) the center of the wheel, and (3) the zero position of the model wheel center.

3. In a last lathe, a swing frame consisting of a bar at the axis of swing, and model and block carriers which are mounted to slide along the bar, the effective radius of swing of the carriers approximating the minimum permitted by the requirement of clearance between the bar and the work-block, a model wheel, and width grading mechanism for moving said wheel from the position in which it effects 1:1 reproduction and for keeping its center upon a line joining this position and the axis of a model carried in the swing frame.

4. In a last lathe, a swing frame comprising a bar at the axis of swing, containing substantially half of the mass of the entire frame, and model and block carriers mounted on the bar, the effective radius of swing of the carriers approximating the minimum permitted by the requirement of clearance between the bar and the work-block, a model wheel, and width grading mechanism for moving said wheel from the position in which it effects 1:1 reproduction and for keeping its center upon a line joining this position and the axis of a model carried in the swing frame.

5. A swing frame comprising an angular bar at the axis of rotation carrying model and block holding instrumentalities, a vertex of one angle of the bar being in the plane containing the axis of rotation of the model and block, the model and block holding instrumentalities being provided with split sleeves embracing the bar, the planes of the splits being perpendicular to the first-mentioned plane, whereby the dogs of the holding instrumentalities will always be set into the same plane irrespective of looseness between the bar and the instrumentalities.

6. In a machine of the class described, a single model and work driving spindle having a driving dog at each end arranged to engage similar but oppositely facing surfaces on a model and a work piece respectively to drive said model and work piece directly, model wheel and cutter carriages, and means to traverse them over the model and work piece, respectively, in opposite directions simultaneously.

7. In a machine of the class described, a unitary model and work driving spindle having dogs constructed and arranged to engage similar but oppositely facing surfaces on a model and a work piece, respectively, model wheel and cutter carriages, and means for traversing the carriages, respectively, over the model and work piece, in opposite directions from the center of the spindle.

8. In a machine of the class described, a unitary model and work driving spindle having dogs constructed and arranged to engage a model and work piece, respectively, in reverse positions, said dogs being shaped to co-operate with similar prepared surfaces on the model and work piece having similar geometrical relations to surfaces having a useful function in the last.

9. In a machine of the class described, a unitary model and work driving spindle having dogs constructed and arranged to engage a model and work piece, respectively, in reverse positions, said dogs being shaped to co-operate with a joint surface on a model last part and last part block, respectively.

10. In a machine of the class described, a unitary model and work driving spindle having dogs constructed and arranged to engage

- a model and work piece, respectively, in reverse positions, said dogs having work and model engaging surfaces which are substantial reflections of each other in respect to a plane perpendicular to the spindle. 5
11. The combination with a model last part having a prepared joint surface, and a last part block having a similar prepared reversely situated, joint surface, of a last lathe having a unitary driving spindle equipped with dogs, the dogs having oppositely facing inclined model and work engaging surfaces constructed and arranged to co-operate with said prepared surfaces to turn the model and block, said dog surfaces being substantial reflections of each other in respect to a plane perpendicular to the spindle and located half way between them. 10
12. In a last lathe, a model wheel carriage, a cutter carriage and a third carriage, means for driving the said third carriage and one of the remaining said carriages in opposite directions, and a grading mechanism the length of which is unaffected at all times by the movement of the machine, but is variable by the operator at will, connecting the third carriage and the other of the two first-mentioned carriages. 15
13. In a last lathe, a model wheel carriage, a cutter carriage and a third carriage, means for driving the said third carriage and one of the remaining said carriages in opposite directions, and a grading mechanism connecting the third carriage and the other of the two first-mentioned carriages, and a swing frame having a central spindle for driving the model and work. 20
14. In a last lathe, a swing frame arranged to carry coaxially a model and block mounted in it, a model wheel and cutter and means for effecting a grading movement of one of the latter two instrumentalities in the plane containing the center of the other and the axes of the model and block. 25
15. In a last lathe, a swing frame arranged to carry coaxially a model and block mounted in it, a model wheel and cutter and means for effecting a grading movement of one of the latter two instrumentalities in the plane containing the center of the other and the axes of the model and block, said swing frame having an effective radius of swing not substantially exceeding that necessary to provide clearance between the axis and the work. 30
16. In a copying lathe, four principal instrumentalities, viz: a model holder, a model wheel, a work holder and a tool, means for causing relative traverses between these instrumentalities taken in pairs, comprising a swing frame, and means for effecting a width grading movement of one of said instrumentalities in the plane containing the centers of the other three. 35
17. In a copying lathe, four principal instrumentalities, viz: a model holder, a model
- wheel, a work holder and a tool, means for causing relative traverses between these instrumentalities taken in pairs, comprising a swing frame, and means for effecting a width grading movement of one of said instrumentalities in the plane containing the centers of the other three. 70
18. In a copying lathe, four principal instrumentalities, viz: a model holder, a model wheel, a work holder and a tool, means for causing relative traverses between these instrumentalities taken in pairs comprising a swing frame, and means for effecting a width grading movement of one of said instrumentalities in the plane containing the centers of the other three, comprising a first member, a second member mounted thereon and carrying the grading-moving instrumentality, said members having movements transverse to each other and to the grading plane, arranged to produce resultant movement in the grading plane. 75
19. In a last lathe, a model wheel carriage, a model wheel thereon and means operated by the relative movement of the model and model wheel to shift the model wheel center transversely to the plane of the model wheel and model centers. 80
20. In a machine of the class described, a swing frame, a width grading slide carrying the model wheel, and means for moving the model wheel transversely to the direction of ordinary width grading movement to keep the wheel on the line joining the zero position of the model wheel with the axis of the model. 100
21. In a machine of the class described, a model wheel carriage, and means for moving the model wheel relatively to the carriage transversely to the direction of ordinary width grading movement, during the cutting of a work piece. 105
22. In a machine of the class described, a model wheel carriage, and means for moving the model wheel relatively to the carriage transversely to the direction of ordinary width grading movement, said means being operated by the relative movement of the model and model wheel. 110
23. In a machine of the class described, a swing frame, a model wheel carriage, and means for moving the model wheel relatively to the carriage transversely to the direction of ordinary width grading movement, said means being operated by relative rotary movement of the swing frame and model wheel. 115
24. In a machine of the class described, a swing frame, a model wheel carriage, a width grading device, and means for moving the model wheel relatively to the carriage transversely to the direction of ordinary width grading movement. 120
- 125
- 130

width grading movement to keep the model wheel in the plane of the model axis and the zero position of the model wheel center.

25. In a last lathe, a pivoted swing frame, a width grading slide carrying one of the four principal instrumentalities of the lathe and operated in time relation to the relative movement of the axis of the model and the model wheel center, and means for moving the center of the said instrumentality relatively to the slide transversely to the direction of movement of the slide during the production of a work piece.

26. In a last lathe, a pivoted swing frame, a width grading slide operated by the relative movement of the axes of the model and model wheel, a model wheel on the slide, and means for moving the model wheel relatively to the slide during the production of a work piece to keep the model wheel substantially in the plane containing the cutter and the axes of the model and work.

27. In a machine of the class described, a swing frame, a model wheel carriage, a grading slide thereon, a movable member mounted on the slide, a model wheel mounted on the member, and means for moving the member in a direction transverse to the line joining the model wheel and model in time relation to the relative movement of the model and model wheel.

28. In a machine of the class described, a swing frame, a model wheel carriage, a grading slide thereon, a movable member mounted on the slide, a model wheel mounted on the member, and a cam operated means for moving the member generally transversely to the line joining the model wheel and model in time relation to the relative movement of the model and model wheel.

29. In a machine of the class described, a swing frame, a model wheel carriage, a grading slide thereon, a movable member mounted on the slide, a model wheel mounted on the member, and a cam operated means for moving the member transversely to the direction of the ordinary width grading movement in time relation to the relative movement of the model and model wheel.

30. In a machine of the class described, a swing frame, a model wheel carriage, a grading slide on the carriage, a lever mounted on the slide, a model wheel on the lever and means for operating the lever during the work production to modify the ordinary width grading movement of the model wheel.

31. In a machine of the class described, a swing frame, a model wheel carriage, a grading slide on the carriage, a lever mounted on the slide, a model wheel on one end of the lever and operating means co-operating with the other end of the lever to shift the model wheel transversely to the direction of ordinary grading movement.

32. In a machine of the class described, a swing frame, a model wheel carriage, a grading slide on the carriage, a lever mounted on the slide, a model wheel on one end of the lever, and a cam co-operating with the other end of the lever to shift the model wheel transversely to the direction of ordinary grading movement.

33. In a machine of the class described, a swing frame, a model wheel carriage, a grading slide on the carriage, a lever mounted on the slide, a model wheel on one end of the lever, and a cam mounted on the main body of the carriage co-operating with the other end of the lever to shift the model wheel so transversely to the direction of ordinary grading movement.

34. In a machine of the class described, a swing frame, a model wheel carriage, a grading slide on the carriage, a lever mounted on the slide, a model wheel on one end of the lever, and a variably positioned cam co-operating with the other end of the lever to shift the model wheel transversely to the direction of ordinary grading movement.

35. In a machine of the class described, a swing frame, a model wheel carriage, a grading slide on the carriage, a lever mounted on the slide, a model wheel on one end of the lever, the other end of the lever being twice as far from the pivot as is the model wheel, and mechanism for controlling the said other end of the lever to keep the model wheel in the line joining its zero position with the axis of the model.

36. In a machine of the class described, a swing frame, a model wheel carriage, a width grading mechanism comprising a grading slide, a lever mounted on the slide carrying the model wheel, and pivoted between its ends, and a slideway co-operating with the lever for moving the model wheel transversely to the direction of normal width grading movement.

37. In a machine of the class described, a swing frame, a model wheel carriage, a width grading mechanism comprising a grading slide, a lever mounted on the slide carrying the model wheel, and pivoted between its ends, and a rotating slideway co-operating with the lever for moving the model wheel transversely to the direction of normal width grading movement, said slideway being connected to the swing frame to turn with it.

38. In a machine of the class described, a swing frame, a model wheel carriage, a width grading mechanism comprising a grading slide, a lever mounted on the slide carrying the model wheel, and pivoted between its ends, and a rotating slideway co-operating with the lever for moving the model wheel transversely to the direction of normal width grading movement, said slideway being connected to the swing frame to turn with it, at substantially the same angular velocity.

39. In a machine of the class described, a swing frame, a model wheel carriage, a width grading mechanism comprising a grading slide, a lever mounted on the slide carrying the model wheel and pivoted between its ends, and a cam developed substantially in accordance with formulae (2) and (3) of the annexed specification for operating the lever.

40. In a machine of the class described, a swing frame, model wheel and cutter carriages, a grading slide on the model wheel carriage carrying the model wheel, and means for modifying the ordinary grading movement of the slide as imparted to the model wheel by adding a component transverse to said ordinary movement to keep the model wheel and cutter in the same plane with the model and work axis, and means for keeping the model wheel and cutter axes equally inclined to this plane.

41. In a machine of the class described, a swing frame, model wheel and cutter carriages, a grading slide on the model wheel carriage carrying the model wheel, and means for modifying the ordinary grading movement of the slide as imparted to the model wheel by adding a component transverse to said ordinary movement to keep the model wheel and cutter in the same plane with the model and work axis, and means for keeping the model wheel and cutter axes equally inclined to this plane, comprising a parallel motion device mounted between the grading slide and the model wheel.

42. In a machine of the class described, a swing frame, model wheel and cutter carriages, a grading slide on the model wheel carriage, and means for modifying the ordinary grading movement of the slide as imparted to the model wheel by adding a component transverse to said ordinary movement to keep the model wheel and cutter in the same plane with the model and work axis, comprising a lever mounted to swing in a plane perpendicular to the axis of the swing frame, a member pivoted to the end of the lever, and carrying the model wheel, and means for maintaining the said member parallel to itself in all positions.

43. In a machine of the class described, width grading mechanism, length grading mechanism and means for adjusting the grading magnifications produced by these mechanisms, said means being placed in convenient proximity to be simultaneously operable by the operator during the production of a work piece.

44. In a machine of the class described, a grading mechanism, means for adjusting said mechanism, a pointer on said adjusting means, and a chart, said chart and pointer being relatively traversed over each other by the feed, whereby the operator may continuously control the grader setting according to a predetermined plan.

45. In a machine of the class described, width and length grading mechanisms, means for setting them to alter their grading effects, pointers in connection with said means moving as the means are set, said setting means being arranged in juxtaposition to be conveniently simultaneously adjusted by the left and right hands of the operator, and a chart, said chart and pointers being relatively moved over each other by the feed whereby the operator may continuously vary the grade in accordance with a predetermined plan, exhibited on the chart.

46. In a pattern copying machine, two carriages, an extensible mechanism uniting them, so the effective length of which is independent of the operation of the machine, and means whereby the operator may alter the length of said mechanism at will during the operation of the machine.

47. In a pattern copying machine two carriages, and a geared mechanism uniting them and holding them normally at an invariable distance during the production of a work piece but arranged for continuous variation of the distance between the carriages, if desired by operation of the gears under the continuous control of the operator during the production of a work piece.

48. In a pattern copying machine, two carriages, and a mechanism joining them, the effective length of which is at all times unaffected by the operation of the machine arranged for accurate but arbitrary and non-predetermined variation of its effective length at any time during the production of a work piece at the will of the operator.

49. In a pattern copying machine, two sliding carriages, an extensible mechanism joining them, the effective length of which is at all times unaffected by the operation of the machine, and a manually operated member arranged to extend or contract the mechanism to effect a positive and definite change in its length at the will of the operator during the production of a work piece to alter the effective distance between the carriages.

50. In a pattern copying machine two sliding carriages arranged to slide on parallel ways, and an extensible mechanism connecting them to maintain a definite distance between them, the said mechanism being manually adjustable to vary the distance during the production of a work piece, and being also constructed to maintain any distance for which it has been set unchanged until it is reset.

51. In a pattern copying machine, two carriages, and a mechanism connecting them comprising a crank arm, and arranged to maintain normally at all times a fixed distance between the carriages, said distance being adjustable, however, by an adjustment of the crank arm, at any time during the production of a piece of work.

52. In a three-dimensional pattern copying machine, model and work holders, a model wheel and cutter, a width grading mechanism connecting the said instrumentalities for pantographically reproducing the model in the work, means for adjusting said grading mechanism comprising a movable member arranged to vary the grading ratio to effect changes in the girth of the work, a pointer and a scale, and a mechanism between the movable member and one of the pointer and scale members constructed and arranged to effect uniform relative movements of the pointer and scale corresponding to movements of the movable member which effect uniform increases in the girth of the work.
53. In a three-dimensional pattern copying machine, model and work holders, a model wheel and cutter, a width grading mechanism connecting the said instrumentalities for pantographically reproducing the model in the work, and means for adjusting said grading mechanism comprising a shaft constructed and arranged to effect uniform increments in girth in the work corresponding to uniform successive rotations of the shaft.
54. In a three-dimensional pattern copying machine, model and work holders, a model wheel and cutter, a width grading mechanism connecting the said instrumentalities for pantographically reproducing the model in the work, and means for adjusting said grading mechanism comprising a swinging arm constructed and arranged to effect uniform steps in girth grade by swinging through successive substantially equal arcs.

In testimony whereof I have signed my name to this specification.

LAURENCE E. TOPHAM.

Certificate of Correction

Patent No. 1,713,792.

Granted May 21, 1929, to

LAURENCE E. TOPHAM

It is hereby certified that error appears in the printed specification of the above numbered patent requiring correction as follows: Page 4, line 106, for " Φ' " read ϕ' ; same page, line 112, for "106" read 106"; page 6, line 30, for " $(g-1)n$ " read $(g-1)r$; line 111, for "o" read θ ; line 125, for " $(1-\cos \phi)$ " read $(1-\cos \phi)$; page 7, lines 14 and 56, for " Φ " read ϕ ; page 11, lines 122 and 123, claim 9, for the word "havings" read *having*; page 12, line 109, claim 21, strike out the comma, and page 14, line 92, claim 47, after the word "desired" insert a comma; and that the said Letters Patent should be read with these corrections therein that the same may conform to the record of the case in the Patent Office.

Signed and sealed this 15th day of July, A. D. 1930.

[SEAL.]

WM. A. KINNAN,
Acting Commissioner of Patents.
